UNITED STATES PATENT OFFICE.

HERAND K. NAJARIAN, OF BONNE TERRE, MISSOURI.

SCREENING MACHINE AND VIBRATING HAMMER THEREFOR.

Application filed August 10, 1923. Serial No. 656,680.

To all whom it may concern:

Be it known that I, HERAND K. NAJARIAN, a citizen of the United States, residing at Bonne Terre, county of St. Francois, and 5 State of Missouri, have invented certain new and useful Improvements in Screening Machines and Vibrating Hammers Therefor; and I do declare the following to be a full, clear, and exact description of the invention, such as will enable others skilled 10 in the art to which it appertains to make and use the same, reference being had to the accompanying drawings, and to the characters of reference marked thereon, which 15 form a part of this specification.

This invention relates to a screening or sifting machine for the separation, into more uniformly sized products, of comminuted materials such as crushed rock and 20 ore, sand, gravel, coal and coke, flour, fertilizer, and analogous substances.

The method of screening I employ is to let the material to be screened run downwards over the surface of an inclinely spaced 25 screen, while said screen is being rapidly vibrated, the fine particles in the said material passing through the openings and going to the undersize and the coarse particles traveling downwards over said screen 30 and passing to the oversize.

My machine essentially consists of an inclinely placed screen frame carrying a screen and yieldingly and resiliently supported on springs from a rigid machine frame, a vibrating hammer suspended on yielding wooden arms and supported from said machine frame, and a transmitter, one end of 35 which is connected to said screen and screen frame and the other cooperating with the vibrating hammer, thus acting as a means for the transmission of the vibrating force 40 from the hammer to the screen.

In my machine, the screen is vibrated with a uniform amplitude and uniform intensity 45 throughout its entire screening area and in a lineal path, and alternately downwardly and upwardly from its initial position of rest, the path of said vibrations being practically normal to the general plane of said 50 screen.

The action of the upward vibrations on the bed of material passing over the screen is such that the finer particles gradually segregate nearer to the surface of the screen 55 as they travel downward over the same, while the coarser particles are thrown away

from the surface of the screen, this process facilitating the passage of the finer particles through the openings in the screen. The action of the downward vibrations is such 60 that particles of material clogging the apertures in the screen are dislodged therefrom at each downward vibration, thus keeping the screening surface at its maximum efficiency. 65

In my machine the force necessary for vibrating the screen as hereinbefore described is obtained by the rapid change of momentum of the heavy vibrating hammer, vibrating during operation, in a closed non-lineal path, as more fully described herein-after. 70

For a more complete explanation of my screening machine and vibrating hammer, reference will be had to the accompanying 75 drawings, in which:

Fig. 1 is a longitudinal section showing the vibrating hammer and the transmitter in section and in their normal inoperative position. 80

Fig. 2 is a cross-section on line 2—2, Fig. 1, showing the ring portion of the transmitter, section of nose shaft and roller toggle, and an end view of the lower portion 85 of said transmitter.

Fig. 3 is a vertical cross-section of my screening machine on line 3—3, Fig. 4.

Fig. 4 is a front view and partial section of my machine, the sectional part being taken on line 4—4, Fig. 3. 90

Fig. 5 is a cross-section of the vibrating hammer, taken on line 5—5, Fig. 1.

Fig. 6 is a diagram illustrating the method whereby vibration is produced in the transmitter by means of change in the path of 95 vibration of the vibrating hammer.

The same reference characters will be used to designate the same parts throughout the several views.

I will first describe the construction and 100 the operation of the vibrating hammer. Referring to Figs. 1 and 5, the vibrating hammer consists of a cylindrical casing 1, which I term vibrator casing, made of suitable material such as cast-iron or steel and for purposes of construction made with varying thicknesses of metal and varying inside and outside diameters throughout its length; a removable end cover 2 having a central opening and fastened to one end of said vibrator 105 casing by means of screws 3; a nose shaft 4 at the opposite end of said vibrator casing,

- one portion of said nose shaft being securely inserted into the end of the vibrator casing and the remainder projecting outwards from said vibrator casing; hollow wings 5 (Figs. 3, 4 and 5) on the outside periphery of said vibrator casing, serving as receptacles for yielding arms 6; a drive shaft 7, one portion of which is within the said vibrator casing and the remainder protruding out through the central opening in the end cover 2 and carrying a drive pulley 8, the portion within the vibrator casing being journaled in bearings 9, one of said bearings securely held inside of said vibrator casing and the other 10 securely held inside the end cover; an unbalanced disc 10 mounted securely on said portion of said drive shaft within the vibrator casing and intermediate the bearings thereof.
- 20 The unbalanced disc 10 comprises a metal disc, preferably circular in section, bored centrally to receive the drive shaft 7 and portions of the disc so cut out as to make it unbalanced with respect to the center-line of 25 said drive shaft. The cavities formed by cutting out portions of said disc are filled with a much lighter material than the material of the disc and carefully smoothed over to make it suitable to run in oil continuously. In Figs. 1 and 5, plugs 11 represent the portions of the unbalanced disc filled with wood. The nut 12 is screwed to one end of the drive shaft 7 and against the bearing, held in vibrator casing, and a bushing 13 is pressed against the bearing held in the end cover 2, thus preventing undue side-wise movements of bearings 9. To reduce friction in the machine, I employ roller or ball bearings and fill the vibrator casing half 30 full of oil to keep said bearings well lubricated, the packing ring 14 being used to seal the opening between the outside periphery of the drive shaft and the central opening in the end cover 2.
- 40 For the purpose of explanation, I will designate the whole vibrating hammer by the reference number 15 (Figs. 3 and 4). The yielding arms 6, which pass through the hollow wings 5 of the vibrating hammer 15, 45 are preferably made of wood and are held at their extremities in pillow blocks 16, which are in turn rigidly fastened to the projecting portions of the rigid machine frame 17.
- 50 When the drive pulley 8 is rapidly rotated, the unbalanced centrifugal force created within the unbalanced disc 10 is transmitted through the bearings 9 to the vibrator casing and as the yielding arms are free 55 to bend in any direction, the entire vibrating hammer 15 vibrates in the path of a distorted ellipse. I call this path the orbit of vibration of the vibrating hammer. This orbit is determined by the magnitude of the unbalanced centrifugal force, the weight of

the vibrating hammer and the flexibility of the yielding arms.

For the purpose of transmitting the vibrating force from the vibrating hammer 15 to the screen frame 18 and screen 19, I employ a transmitter 20 (Figs. 1, 2, 3 and 4), one end of said transmitter being flanged and rigidly connected to bracket 23, which is in turn rigidly connected to said screen frame 18. The other end of the transmitter 75 is designed to cooperate with the vibrating hammer as follows:

Referring to Figs. 1 and 2, on the protruding portion of the nose shaft 4 is mounted a roller 21, bored to fit rotatably on said protruding portion of the nose shaft. The outside periphery of the roller is made circular in cross-section and in its normal inoperative position does not touch any part of the transmitter. Theoretically, it is not 85 essential that the roller shall not touch the transmitter while inoperative and I do not want to confine myself to the construction shown, but for the proper operation of the machine for the purposes that it is used, I prefer to have a space left between the co-operating surfaces of the roller and the transmitter, as fully explained hereinafter.

The ring portion of the upper end of the transmitter 20 is bored to receive a removable ring 22 snugly fitted so that it will not turn when the machine is in operation. The inside periphery of ring 22 is so designed that when the vibrating hammer is in operation, one or more portions of said inside surface cooperates with the roller toggle 21 while other portions of said surface do not touch the roller toggle. This is done to transmit force through the transmitter at any desired direction according 105 to the requirements of the machine.

In my screening machine, I have found that the best results are obtained when the screen is vibrated twice during each complete cycle of vibration of the vibrating hammer, or alternately downwards and upwards, hereinbefore mentioned. Consequently, I make the inside surface of the ring 22 so that there are two oppositely placed surfaces adapted to cooperate with the roller toggle 21. This is accomplished by boring the inside of ring 22 oblong, making the diameter of the ring on axis X-X much larger than the diameter on axis Y-Y. The transmitter is so placed that axis Y-Y is substantially normal to the general plane of the screen and the screen frame. Thus the surfaces on the inside of ring 22, which are at the extremities of its short axis Y-Y, are closer to the outside circular periphery of the roller toggle 21 than the remainder of said inside surface and during operation the transmitter vibrates alternately in the directions of arrows "M" and "N". The distances between 110

these aforementioned surfaces, represented in Fig. 2 by "a" and "b" are governed by the requirements of the machine, usually made one sixty-fourth to one thirty-second 5 of an inch. The distances represented by "c" and "d" are made so that the roller will not come in contact with them during operation. In practice I have found that the distances "c" and "d" each should be 10 slightly larger than one-half the average diameter of orbit of vibration of the vibrating hammer. Thus, if the weight and the speed of the vibrating hammer are so proportioned that it vibrates in an orbit of 15 about one-fourth of an inch in diameter, the distances "c" and "d" are made slightly greater than one-eighth of an inch.

Referring to Fig. 6, let broken line 24 represent the orbit of vibration of the 20 vibrating hammer in a very much enlarged form. Let 25 represent the roller and assume that the mass of the vibrating hammer is concentrated in the roller. Let 26 represent one of the inside cooperating surfaces in ring 22. Assuming that the roller 25 toggle is traveling on its orbit 24 in the direction of the arrow 27 when said roller meets the surface 26, a reactionary force, represented by arrow 28, will act on the 30 roller diverting said roller from its orbit 24 to a new orbit represented by dot-and-dash line 29. The reactionary force is due mainly to the resistance of the springs and also to the weight of parts vibrated. The 35 force in the roller acting against this surface 26 is equal in magnitude and opposite in direction to the reactionary force represented by arrow 28. The new orbit of vibration is shorter in circumference and as 40 the weight of the vibrating hammer is constant and the time of one complete vibration is also constant, the result is retardation in velocity and lessening in momentum of the vibrating hammer. This change 45 in momentum is entirely dependent on the reactionary force that can come against the surface of the roller from the cooperating surface inside the ring 22. The force exerted against the surface 26 from the roller 50 25 is equal to force 28 and opposite in direction, said force acting against the force of the springs will move said surface 26 from its position 30 to position 31 during the upward travel of the roller in its orbit 55 and as the roller travels downward to position 32, said surface follows and reaches its original position, thus completing one vibration of the transmitter. Hence, the number of such cooperating surfaces in 60 ring 22 determines the number of vibrations of the transmitter for each cycle of vibration of the vibrating hammer in its orbit.

During the operation of the machine the roller 21 revolves on the nose shaft 4 very 65 slowly, due to slight friction between the

cooperating surfaces. This serves the very useful purpose of distributing the blows over the entire outside surface of the roller, thus eliminating uneven wear on the toggle. In order to lubricate the cooperating 70 surfaces properly, I provide a cover 33 for the open end of the transmitter ring, said cover being fastened to the transmitter ring by screws 34 and provided with a central oil hole 35, and an oil hole cover 36. 75

The side edges 37 of the screen 19 are turned upwards to act as baffles to prevent coarse material going to the undersize. The screen frame 18 is fastened to the springs 38 by means of bolts 39, said bolts 80 holding said screen frame and said spring rigidly together through lugs 40 on the screen frame and lugs 41 fastened to the springs. The springs are rigidly fastened to the projecting angles 42 of the machine 85 frame 17.

I do not want to confine myself to the specific construction details shown herein, as different screening problems require specific details to be incorporated in the construction of the machine. 90

Having now described my invention, what I claim as new is:

1. In a screening machine comprising a support, a vibrating hammer yieldingly supported from said support and vibrating in a closed nonlineal path during operation, a single roller rotatably mounted on said vibrating hammer and vibrating therewith, a screen carried on a screen frame and yieldingly supported on springs, a transmitter rigidly connected to said screen frame and screen, a ring forming a part of said transmitter and having one or more portions of its inside surface adapted to come 100 in contact with said roller a given number of times during a rotation of said rollers, thereby causing change in momentum of the vibrating hammer and generating force which vibrates said transmitter and said 105 screen in the direction of said force.

2. In a screening machine, a transmitter, one end of which is flanged and adapted to be secured to a screen frame, the other end comprising a cylindrical ring, portions of 110 the inside surfaces of said ring so distanced from its centerline as to make parts of said ring surfaces at a shorter distance from the centerline of said ring than others thereby affording surfaces to co-operate with the 115 outer surfaces of a single roller rotatably mounted on a vibrating hammer when in operation and thereby causing a vibratory force to be generated acting normal to the 120 cooperating surfaces thereof.

3. A vibrating hammer comprising a cylindrical casing, a removable end cover at one end of said casing with a central opening, a removable nose shaft securely inserted at the other end of said casing, part of said 125

- 4
5. A nose shaft projecting from said end of the casing, a roller rotatably mounted on a projecting portion of the nose shaft, an unbalanced disc within said casing and mounted on a drive shaft, one portion of said drive shaft journaled within the casing on two bearings carrying the unbalanced disc intermediate the said bearings, and the other end of said drive shaft protruding out through the central opening in end cover and carrying a drive pulley and hollow wings on the outside periphery of said casing for the reception of yielding arms. 55
6. A vibrating hammer comprising a casing having an axial opening extending therethrough, a bearing secured in said opening, a cap removably secured to the end of the casing, a second bearing secured in said cap, an unbalanced disc mounted on the shaft intermediate the said bearings, a drive pulley on the end of the drive shaft, a second shaft secured to the casing and projecting from the same, and a transmitter member provided with an opening for the reception of the last named shaft. 60
7. A vibrating hammer comprising a casing, a cylindrical portion projecting from one end of said casing, a cap closing the other end of said casing, a pair of bearings supported in the casing, a shaft rotatably mounted in said bearings, an unbalanced disc mounted on the shaft between said bearings, a drive pulley secured to said shaft, and a transmitter having one end adapted to be secured to a screen and the other provided with a non-circular opening adapted to receive said cylindrical portion and to cooperate therewith. 65
8. A vibrating hammer comprising a casing having an axial chamber of substantially circular cross-section, one end of said chamber being of smaller diameter than the other, a shaft having one end secured in said opening of reduced diameter and having the other end projecting outwardly from the casing, a roller mounted on the projecting portion of said shaft, a cap secured to said casing and adapted to close the other end thereof, a bearing secured in the casing, a second bearing secured to the cap, a shaft rotatably mounted in said bearings, a circular disc on said last named shaft, said disc having a central opening adapted to receive the shaft, portions of said disk being cut out unsymmetrical to the axis thereof, said cut out portions being filled with a lighter material so as to make the disk unbalanced, 100 means for yieldingly supporting said casing, and means for rotating said shaft and disk at a high rate of speed whereby the casing will be caused to oscillate.
- In testimony whereof I affix my signature.
- HERAND K. NAJARIAN.
